ELECTRIC LAMP SOCKET SHELL

George Henry Elwell, New Haven, Conn., assignor
to The Greist Manufacturing Company, a cor-
poration of Connecticut

Application August 17, 1927, Serial No. 213,669

2 Claims. (Cl. 173—362)

The invention relates to improvements in electric lamp socket shells and especially to the manner of impermanent assembly of a socket shell and a shade holder, and the object of the invention is to provide the shell of a lamp socket with a screw-thread not only adapted to receive a corresponding thread of a part to be thereby assembled to the shell, but to bindingly obstruct that part upon the completion of the assembly.

- 10 The following is the description of the invention, reference being had to the accompanying drawing (one sheet) in which the Figure 1 is a side elevation of a socket shell provided with the improvement; the Figure 2 is an opposite 15 side elevation of the same shell; and the Figure 3 illustrates more clearly the course of the thread formed in the shell. While the improvement is illustrated only in connection with an electric lamp socket shell it will be obvious that it may 20 be applied to the construction of any screw-thread, and this wide application of the invention is hereby anticipated.

Referring more particularly to the drawing, in which similar parts are similarly numbered, the 25 ordinary type of electric lamp socket shell is illustrated as having the shell 1 and the cap 2 separably assembled in any desired manner known to the art. Rolled, or otherwise formed in the metal of the shell 1 adjacent its lamp 30 receiving end, is the screw-thread 3 encompassing the periphery of the shell 1. The course of this screw-thread 3, in a manner well known to the art, continuously emerges from one to the next of the several parallel radial planes of the lamp 35 socket in which the thread lies. The formation and course of the thread end 4, however, constitutes the improvement provided by this invention and, while the thread end 4 is an unbroken and unobstructed continuance of the

screw-thread 3, beginning as at 5 and continuing (as illustrated in dotted line by the Figure 3) around the opposite side portion of the shell 1 and ending on the visible portion of the shell 1, as at 6, its course in substantially encompassing the shell 1 lies throughout its length in one and the same radial plane of the lamp socket. Previous to this improvement it was thought necessary to provide an annular shoulder, by means of a special beading or other formation of the shell, against which the annular edge of an internally threaded shade holder (not illustrated) might engage in a parallel plane thereto to limit and bindingly lock the holder in its threaded assembly upon an externally threaded shell. This 10 improvement, however, provides for the threaded assembly of such a holder upon the screw-thread 3 and against the thread end 4 with a similar result and therefore not only eliminates the necessity of providing a special beading, but produces in a single operation of construction a single thread element capable of the dual accomplishment of providing a threaded assembly and also a binding limitation of that assembly tending to hold the assembled part rigidly in place.

What I claim is:—

1. An electric lamp socket shell having a cylindrical wall and strands of a screw-thread formed upon and encircling said wall, the top strand of said screw-thread being in a plane normal to the axis of the shell for the purpose herein set forth. 30
2. An electric lamp socket shell having a cylindrical wall and projecting strands of a screw-thread formed in said wall, the top strand of said screw-thread being in a plane normal to the axis of the shell for the purpose herein set forth.

GEORGE HENRY ELWELL.
